(57) **CLAIM**

The ornamental design for a user interface for a patient monitor, as shown and described.

DESCRIPTION

A portion of the disclosure of this patent document contains material to which a claim for copyright is made. The copyright owner has no objection to the facsimile reproduction by anyone of the patent document or the patent disclosure, as it appears in the file or records of the U.S. Patent and Trademark Office, but reserves all other copyright rights whatsoever.

The single FIGURE is a front view of a user interface for a patient monitor showing our new design.

The broken line showing of a patient monitor display, icons, and alphanumeric text is for illustrative purposes only and forms no part of the claimed design.
